UNITED STATES PATENT OFFICE

RICHARD SMYTHE GUINNESS, OF BIRMINGHAM, ENGLAND

WASHBASIN

Application filed April 12, 1920, Serial No. 443,750, and in Great Britain April 25, 1929.

This invention relates to wash basins and refers more particularly to wash basins such as are intended for use in confined spaces such as railway or ships' sleeping compartments or other vehicles or in small flats.

The primary object of the present invention is to provide a wash basin of the above kind of a generally improved construction and which furthermore can be used conveniently with a fixed table or shelf beneath which it is normally disposed, whilst when required for use it may be withdrawn from beneath the table or the like by swinging the basin outwardly upon its vertical axis until it is clear of the table or other structure.

In accordance with the present invention I provide a wash basin including a substantially vertical tube, upper and lower supports for said tube, a basin proper mounted on and supported by said tube intermediate its upper and lower supports, said basin being adapted to swing or pivot about the axis of the tube.

A further feature of the invention is to construct the wash basin as a self contained unit ready for application to a fixed supporting surface, the unit being adapted for connection with one or more water supply and discharge pipes and including suitable valves or taps for controlling the supply and discharge of water.

A further object of the present invention is to provide an arrangement whereby the basin has adequate strength so that it will not be liable to be damaged during use and in accordance with this feature, the basin is provided with a deep depending lip at its periphery, and this lip preferably embraces the pivot associated with the basin.

Referring to the drawings:—

Figure 1 is a view in side elevation of one form of the apparatus showing the basin in the position it occupies when required for use.

Figure 2 is a plan view corresponding with Figure 1.

Figure 3 is a sectional view in side elevation showing the basin pivot and fittings.

Figure 4 is a sectional view on line 4—4 of Figure 3.

Figure 5 is a sectional view on line 5—5 of Figure 3.

Figure 6 is a sectional plan view upon an enlarged scale showing one of the inlet valves.

Figure 7 is a plan view showing a modification.

Figure 8 is a section on line 8—8 of Figure 7 on an enlarged scale.

Figure 9 is a section on line 9—9 of Figure 8.

In the construction illustrated the pivot may consist of a vertical tube 1 mounted so that it can turn in upper and lower bearings 3 and 4.

The upper bearing which may be formed in a member 15 includes a boss 3^a for receiving the upper end of the pivot tube and within this boss is fixed a tubular shield 6 depending down into the upper end of the hollow pivot tube.

The member 15 which may conveniently be formed as a casting, forming the upper bearing 3 may also include an attachment portion 7 by which it may be secured to the wall, and a pair of casing portions 8 arranged side by side and each provided with a boss 9 for receiving a water supply pipe. Each casing portion is adapted to receive a tap or valve.

Behind the pivot tube 1 and beneath the back portion of the member 15 is a bracket 43 which carries two pipes 44 one being attached to each of the bosses 9. The one pipe 44 conveys hot water and the other cold water.

Each of the taps comprises a cylindrical valve 45 having a rubber or other washer 46 and arranged to open upwardly.

Each valve 45 is pressed downwardly by a spring 47 and is opened by means of a pair of rockers 48 supported on shoulders 49 formed within the casing portions 8 of the member 15.

The rockers 48 are provided with trunnions 50 and the rockers are operated by pins 51 to each of which is attached a knob 52. Each pin 51 is provided with a flange 53 forming an abutment for a spring 47 and each pin slides in a screwed cap 54 the arrangement being such that when the knob 52 is pressed

downwardly the rockers are turned on their trunnions so as to raise the valve 45 to open it.

When water is admitted by either or both taps or valves it passes into the upper end of the pivot tube 1 but the upper part of this tube 1 is divided by a partition 11 from the lower portion so that the upper portion of the pivot sleeve forms a water admission chamber 12.

10 The partition by which this chamber is formed also includes an inner tube 13 having its lower end connected to the partition 11, the inner tube 13 extending to the top of the casting 15.

15 This casting 15 is provided with an opening at the top and the opening has a cap 5 which may be provided with a depending sleeve 16 engaging in or around the top of the partition tube 13.

20 The lower bearing 4 for the pivot tube 1 may also take the form of a casting having an attachment portion 30 whereby it may be fastened to the bracket 43 and it may also include a stuffing box 17 in order to make a liquid tight connection with the lower part of

25 the tube 1, it being understood that the pivot tube turns when the basin is moved; the two bearings, of course, remaining stationary.

The lower part of the lower bearing 4 is 30 formed as a water discharging outlet 23 and may be screwed so that a waste pipe or a siphonic trap may be secured thereto and above this discharge portion the lower bearing may be formed as a valve seat 18.

35 The valve working on this seat may consist of a sliding tube 19 arranged centrally through the pivot tube 1 and sliding axially therein, this tube 19 being provided with a collar or shoulder 20 near its lower end under 40 which is a rubber or other washer 21 adapted to engage the valve seat 18 and form a closure.

The tube 19 beneath the rubber or other washer is provided with a number of holes 22 so that when the tube is raised the water can 45 pass through these holes and into the water outlet 23.

The tube 19 extends up through the pivot tube 1 and at a suitable position approximately on a level with the upper part of the basin 50 25 further holes 26 are provided therein so that an automatic overflow escape is thus provided.

55 At its upper end the tube 19 is provided with a plug 27 having a stem 24 to which a pin 28 is attached, this pin passing through a bearing in the cap 5 and being provided with a knob 29 so that it can be lifted when it is desired to discharge the water.

60 If required, the cap 5 may be provided with an internal shoulder 55 and vertical guide 56 while the pin 28 is provided with a radial projection 57 which is adapted to ride up the guide 56 and to engage the shoulder 55 when 65 the knob 29 is given a part turn. This pro-

vides a means of keeping the water outlet valve open when desired.

Instead of using this arrangement we may provide for the automatic operation of the valve tube 19 when the basin is swung into 70 and out of use and the arrangement may be such that the outlet valve is automatically opened when the basin is swung into its "out of use" position.

This may be effected by providing a lateral 75 projection on the stem 24 or on the pin 28, this projection being engaged by a helical or other suitably shaped cam provided within the tube 13 and affixed thereto so that it rotates there- 80 with.

Alternately, the tube 13 may be provided with an inward radial projection engaging a helical or other cam either on the stem 24 or on the pin 28.

If this arrangement is provided then the 85 tube 19 will be automatically raised when the basin is swung into its "out of use" position and it will be kept raised until the basin is returned to its "in use" position.

If this arrangement is used it will not interfere with the manual operation of the valve tube 19 when the basin is in its "in use" position.

A spring may be provided acting upon the water outlet tube 19 and normally retaining 95 it in its lower or closed position.

Instead of providing a number of small openings in the lowest part of the basin as shown and allowing the water to flow freely therethrough into the pivot tube 1, the lowest part of the basin may be provided with an outlet fitting of the well known type including a bush which receives a plug attached to the basin or adjacent to the structure by a chain. If such an arrangement is used then 100 the tube 19 and associated parts may be omitted, and an overflow tube may be provided connecting the upper part of the basin with the tube 1.

The basin 25 may be of any suitable or usual form preferably forming a bowl and this bowl is connected at its upper part with the upper part 12 of the pivot tube 1 the connection being formed by a pipe 31 which forms the water inlet pipe to the basin.

110 At its lowest part the basin is provided with a grating 32 beneath which is an outlet fitting 33 which may be provided with a removable plug 34 if desired, this outlet fitting 115 being connected by a pipe 35 to the lower part of the pivot tube 1.

The upper part of the basin is preferably provided with an inwardly and downwardly projecting lip 36 so as to prevent the water 125 from splashing or overrunning the edges of the basin and this lip may be extended upwardly and outwardly where it is bent down to form a lip 37 connected to a deep body 38 which extends around the periphery of the 130

basin and also embraces and is secured to the pivot tube 1.

This body forms a wall extending around the basin and is of a depth somewhat greater than the depth of the basin so that the inlet and discharge pipes 31 and 35 which extend between the pivot tube and the basin are enclosed thereby.

The upper part of the basin may be provided with suitable recesses 39 or receptacles for retaining soap and sponge or brushes.

It will be observed that the upper part of the pivot tube which is partitioned so as to form the water inlet chamber 12 is not normally under water pressure as no water can enter this chamber until one of the taps is turned on. When a tap is turned on the water flows through the water inlet chamber, and through the inlet pipe 31 to the basin, the water flowing thence through the water discharge pipe 35 and into the lower part of the pivot tube which it fills to the same level as the water in the basin.

By this means the interior of the lower part 25 of the pivot tube 1 is kept clean as it is automatically washed out every time the basin is filled.

In the arrangement shown in Figures 7, 8, and 9, the outlet valve 21 is automatically opened when the basin is swung into its "out of use" position and the outlet valve 21 is automatically closed when the basin is swung into the position it is to occupy when used. Further, the arrangement shown in Figures 35 7, 8, and 9 also permits the outlet valve 21 to be operated by the knob 29 at any time if desired.

Referring to Figures 7, 8, and 9, the stem 24 which is fixed to the tube 19 is provided 40 with the pin or extension 28 terminating in the knob 29 and the pin 28 is provided with a radial projection 60.

The cap 5 is fixed to the upper bearing 15 and constitutes a fixed sleeve which is provided with a bayonet slot 61 in which the pin 60 can slide, the vertical part of this bayonet slot 61 preventing the pin 28 and the stem 24 from turning on their own axes but permitting vertical sliding movement.

50 The upper end of the partition tube 13 is provided with a fixed bush 62 secured in position by a screw 63 and having a cam face 64 which is adapted to engage the pin 60, the arrangement being such that when the basin is swung the partition tube 13 swings with it and thus rotates the bush 62 causing the stem 24 to be raised by reason of the fact that the cam face 64 engages the pin 60. The arrangement is such that the stem 24 and

60 tube 19 carrying the outlet valve 21 are automatically raised to open the outlet valve when the basin is swung into its "out of use" position, the outlet valve 21 being automatically closed when the basin is swung back into

65 the position it occupies in use.

A cover 40 for the basin, said cover forming a table may be provided and such cover may be of wood or any other suitable material and this table may be cut away so that the member 15 for the pivot tube can be mounted therein.

The member 15 may be provided with a spring pressed pin 41 or other form of automatic catch co-operating with one, two or more recesses 42 in a plate secured to the upper part of the basin, for retaining the basin in any of various definite positions.

Further, definite stops may be provided for the basin at its two terminal positions and the basin may be provided with a handle to enable it to be easily pulled out and pushed in.

It is to be understood that the basin and associated parts may be made of metal, porcelain, or any other suitable material.

Claims:

1. A wash basin comprising a substantially vertical tube, an upper support for said tube, said upper support being of hollow box-like form and having an inlet opening for water, a valve in said opening, an operating member for said valve projecting through the top of said upper support, a lower support for said tube, and a basin mounted on and supported by said tube intermediate said upper and lower supports, said basin being mounted to swing horizontally about the axis of said tube.

2. A wash basin comprising a substantially vertical tube, an upper support for said tube, a lower support for said tube, a partition within said tube and disposed intermediate said supports, said upper support being of hollow box-like form and having an inlet opening for water, said lower support having an opening forming an outlet for water, and a basin mounted on and supported by said tube intermediate said upper and lower supports, said basin being mounted to swing horizontally about the axis of said tube.

3. A wash basin comprising a substantially vertical tube, an upper bearing for said tube, a lower bearing for said tube, a basin fixed to and supported by said tube intermediate said

upper and lower bearings, said basin being mounted to swing horizontally about the axis of said tube, said upper bearing forming a water inlet chamber, said lower bearing having an opening forming an outlet for water, a partition in said tube intermediate said bearings, said partition having a tubular extension, extending through said upper bearing, and a valve controlling said water outlet opening.

4. A wash basin comprising a substantially vertical tube, an upper bearing for said tube, a lower bearing for said tube, a basin fixed to and supported by said tube intermediate said upper and lower bearings, said basin being mounted to swing horizontally about

the axis of said tube, said upper bearing forming a water inlet chamber, said lower bearing having an opening forming an outlet for water, a partition in said tube intermediate said bearings, said partition having a tubular extension, extending through said upper bearing, a valve controlling said water outlet opening, said valve consisting of a tube having an external flange, and having openings in its upper part, whereby it also operates as an overflow passage.

5. A wash basin comprising a substantially vertical tube, an upper bearing for said tube, a lower bearing for said tube, a basin fixed to and supported by said tube intermediate said upper and lower bearings, said basin being mounted to swing horizontally about the axis of said tube, said upper bearing forming a water inlet chamber, said lower bearing having an opening forming an outlet for water, a partition in said tube intermediate said bearings, a valve controlling said water outlet opening, a pipe connecting the upper part of said tube with the upper part of said basin, and a pipe connecting the lower part of said basin with the lower part of said tube.

6. A wash basin comprising a substantially vertical tube, an upper bearing for said tube, a lower bearing for said tube, a basin fixed to and supported by said tube intermediate said upper and lower bearings, said basin being mounted to swing horizontally about the axis of said tube, said upper bearing forming a water inlet chamber, said lower bearing having an opening forming an outlet for water, a partition in said tube intermediate said bearings, said partition having a tubular extension, extending through said upper bearing, a valve controlling said water outlet opening, a stem on said valve whereby it may be operated, a projection on said stem, a fixed sleeve having a slot in which said projection engages so as to prevent said stem from turning while permitting it endwise movement, a bush in the end of said tubular extension, said bush having a cam face for raising and lowering said stem when the basin is turned, said cam face being engaged by the projection on said stem.

7. A wash basin comprising a substantially vertical tube, an upper bearing for said tube, a lower bearing for said tube, a basin fixed to and supported by said tube intermediate said upper and lower bearings, said basin being mounted to swing horizontally about the axis of said tube, said upper bearing forming a water inlet chamber, said lower bearing having an opening forming an outlet for water, a partition in said tube intermediate said bearings, said partition having a tubular extension, extending through said upper bearing, a valve controlling said water outlet opening, a stem on said valve whereby it may be operated, a projection on said stem, means to prevent said stem from turning on

its own axis, and means to raise and lower said stem automatically when said basin is swung.

8. A wash basin comprising a substantially vertical tube, an upper bearing for said tube, a lower bearing for said tube, a basin fixed to and supported by said tube intermediate said upper and lower bearings, said basin being mounted to swing horizontally about the axis of said tube, and means for checking said swinging action at a plurality of positions.

In witness whereof I affix my signature.
RICHARD SMYTHE GUINNESS.
